AUTOMATIC MACHINE FOR MAKING PAPER CONTAINERS

Luther K. Funkhouser, Dayton, and Ralph W. Carnahan, near Dayton, Ohio; said Carnahan assignor to said Funkhouser

Application April 7, 1934, Serial No. 719,448
Renewed February 12, 1936

41 Claims. (Cl. 93—39)

This invention relates to new and useful improvements in automatic machines for making paper containers.

It is the principal object of our invention to provide an automatic machine for making liquid-tight paper containers in a rapid and sanitary manner without the use of a paraffin or other liquid-proof coating.

It is another important object of our invention to provide an automatic machine for making liquid-tight paper containers continuously from a roll of paper fed into the machine.

It is still another object of our invention to provide an automatic machine for making liquid-tight paper containers in several sizes simultaneously, or selected ones of said assorted sizes.

Another object of our invention is to provide an automatic machine for making liquid-tight paper containers progressively and simultaneously in various steps.

It is another important object of our invention to provide an automatic machine for making liquid-tight containers employing novel adhesive applying means, neck forming means and automatic means for inserting and seaming the bottom of the container.

It is yet another important object of our invention to provide an automatic machine for making liquid-tight paper containers employing novel transfer means to move the container forwardly as each step is performed.

Another important object of our invention is to provide an automatic machine for making liquid-tight paper containers having ejector and conveyor means for the completed containers.

The invention may be embodied in machines that vary in form and in structure, and are designed and constructed for use in continuously and automatically forming liquid-proof paper containers, such as milk bottles, from a roll of paper in either one size or various sizes.

While the principal objects of this invention are stated above, others will appear in the following specification describing the embodiment of the invention set forth in the accompanying drawings.

In these drawings, Figure 1 is a front view of the complete automatic machine for making liquid-tight paper containers. Figure 2 is an end view of the paper-receiving end of the machine.

Figure 3 is an end view of the discharge end of the machine. Figure 4 is a sectional plan view taken on the line 4—4 of Figure 1, showing the neck and bottom forming tools in section. Figure 5 is a cross sectional view taken on the line 5—5

of Figure 1, showing the feed, shearing and cylinder forming rolls in section. Figure 6 is a cross-sectional view taken on the line 6—6 of Figure 1, showing the tool head indexing means. Figure 7 is a detail view of the tool head for crimping and sealing the container bottom in place. Figure 8 is a detail sectional view of the tool head shown in Figure 7 and taken on the line 8—8 of that figure. Figure 9 is an enlarged sectional view taken through the neck forming tool used with the first operation. Figure 10 is an enlarged sectional view taken through the neck forming tool used with the second neck forming operation. Figure 11 is an enlarged detail sectional view taken through the bottom transfer tool. Figure 12 is an enlarged sectional view taken through the co-acting neck forming dies. Figure 13 is a side view of the rotary die bracket and driving means. Figure 14 is an enlarged sectional view of the cylinder forming mandrel. Figure 15 is a view of the container as produced at the first stage.

Figure 16 is a view of the container formed in the first stage after further forming operations during the second stage. Figure 17 is a vertical sectional view as completed at the third stage. Figure 18 is a general view of a multiple machine for simultaneously making liquid-tight containers in three different sizes, such as quarts, pints and half-pints.

In the form of construction, illustrated in the drawings, the paper forming the container, except its bottom, is fed from a supply roll supported upon a rack (not shown). When the paper enters the machine, it is received between continuously rotating upper and lower feed rolls 1 and 2 for delivery to intermittently operated gauge and shear rolls 3 and 4 positioned adjacent the feed rolls.

The feed rolls 1 and 2 have at one end thereof axial extensions 5 and 6 journaled in bearings 7 and 8 formed in the end frame 9; and at their opposite ends these axial extensions are journaled in bearings 10 and 11 provided in a transverse support 12. (See Figures 1, 2, 4 and 5.)

The end frame 9 is substantially square, having corner members 13 and 14 connected by transverse top, bottom and intermediate members 15, 16 and 17, respectively, reinforced and stiffened by ribs formed on their inner faces. Opposite the end frame 9 is a right end frame 18, similar to the former and having top, bottom and intermediate transverse members 19, 20 and 21 respectively, likewise stiffened by ribs provided on their inner faces. The frames 9 and 18 are inter-

connected at their respective corner members by front longitudinal members 22 and 23 bolted to the end frames, and rear longitudinal members 24 and 25, likewise bolted to the end frames 9 5 and 18. (See Figures 1 to 4 inclusive.)

The axial extensions 5 and 6 of the feed rollers 1 and 2 adjacent their bearings 7 and 8, are provided with mating gears 26 and 27, by which they are rotated in unison. (See Figures 1 and 10 2.)

Mounted on the upper shaft 5 is a V-pulley 28 which receives a V-belt 29 that passes over a similar V-pulley 30 keyed to a main longitudinal drive shaft 31, by which the feed rollers are rotated. (See Figure 5).

The shaft 31 is journaled at each end in bearings 32, 32 provided in the end frame 9, and another transverse support 33. Adjacent its center, the shaft 31 is connected through a gear reduction drive 34 with a motor 35, below it. This motor is mounted upon a bed plate 36 extending longitudinally of the machine and supported by the bottom transverse end frame members 16 and 20. (See Figure 2.)

Beyond the bearing 32 in the end frame 9 there are keyed to the shaft 31, spaced intermittent gears 37 and 38, adapted to mesh with pinions 39 and 40 respectively above them. The pinion 40 is keyed to a sleeve shaft 41 journaled in an end frame bearing 42 and having secured to its other end a lock disc 43. Rotatably mounted within the sleeve 41 is another shaft 44 to whose outer end the pinion 39 is secured, and to whose opposite end another lock disc 45 is secured.

Co-acting with the lock discs 43 and 45 are lock discs 46 and 47 respectively keyed to the shaft 31 adjacent the inner face of the frame 9. The intermittent gear 37 has a pitch diameter four times that of the mating pinion 39, the 40 teeth of the gear 37 occurring on 270 degrees of its periphery and joined by an undercut portion 48. Likewise, the lock disc 47 has an undercut portion 47a co-extensive with the toothed portion of the gear 37. (See Figures 1, 2 and 4.) Formed 45 on the periphery of the lock disc 45 engaged by the disc 47, is an arcuate depression 49 in which the periphery of the larger lock disc 47 is afforded a clearance.

When the shaft 31 is rotated, the outer periphery of the disc 47 will turn through the depression 49, and the pinion 39 and its lock disc 45 will be stationary, locked against rotation by the engagement of the lock discs 45 and 47.

Now, when the toothed portion of the gear 37 55 engages the pinion 39, the latter will make three complete revolutions before the toothed portion passes out of engagement with it, and during its rotation, the periphery of the lock disc 45 will be rotated in the clearance afforded by the 60 undercut portion 47a of the disc 47.

The gear 38 is like the gear 37, except that its teeth occur upon only 90 degrees of its periphery, the teeth starting in alignment with the teeth of the gear 37, and its respective lock 65 disc 46 has an undercut portion 50 co-extensive with the toothed portion of the gear 38.

When the shaft 31 is rotated, the gear 37 will cause its pinion 39 to make three complete revolutions and, starting simultaneously with the rotation of the pinion 39, the gear 38 will cause its 70 respective pinion 40 to make only one revolution. (See Figures 1, 2, 4 and 5.)

Meshing with the pinion 39 is an idler pinion 51 of equal diameter. Secured to this pinion is 75 an idler gear 52. Meshing with the pinion 40

is an idler pinion 53, also of equal diameter and having secured thereto another idler gear 54. The pinions 51 and 53 with their respective gears 52 and 54, are freely mounted on a stud 55 projecting from the outer face of the frame 9. 5 Meshing with the gear 54 is a gear 56 of like diameter and secured to the axial projection of the shaft 57 for the lower gauge and shear roll 4. The opposite end of this shaft 57 is journaled in a bearing 58 provided in the support 12 10 (see Figure 4).

Also meshing with the gear 52 is a gear 59, of like diameter, secured to the projecting end of a mandrel 60. This mandrel 60 is received by an axial housing 61 formed in the top member 15 and in which it is journaled in spaced ball bearings 62 and 63 in counterbores in its inner and outer faces.

It is evident that the continuously rotating feed rollers 1 and 2 will draw the paper into the 20 machine constantly as used. (See Figures 1, 4 and 5.)

The intermittently turning gauge and shear rolls 3 and 4, being slightly larger than the mandrel, will make one complete revolution, thereby 25 introducing a length of paper sufficient to form an overlapping layer upon the mandrel 60, said overlapping portion forming a longitudinal adhesive coated seam to be hereinafter referred to.

Longitudinally positioned in registering positions on the periphery of the rolls 3 and 4, are co-acting rotary shear blades 64 and 65 which, with each revolution of these rolls, will sever the length of paper above referred to. (See Figure 5.)

The introduction of the piece of paper required to form the container occurs during a single complete revolution of the rolls 3 and 4. This paper is then received by a forming cylinder 66 adjacent the roller 4. The cylinder 66 is 40 rotatably mounted with the mandrel 60, and consists of a cylindrical sleeve 67 supported, adjacent the bearing 63, upon a flange 68 surrounding the mandrel 60. At its opposite end the cylinder is supported upon another flange 69 at the 45 inner unsupported end of the mandrel.

Axially slidable within the mandrel 60 is an ejector shaft 70 whose one end extends through the end of the mandrel beyond the gear 59. To the inner end of the shaft 70 there is secured a 50 conical end member 71 shaped to form the neck of the container as shown in Figure 16. This conical end member is essentially a male rotary die rotatable with the mandrel 60 and having formed on its periphery spaced axial ribs 72, varying from their maximum height at the outer reduced end of the conical end member 71, to their inner end, where the ribs converge with the surface of the conical end member.

Formed in diametrically opposite sides of the 60 wall of the cylinder 67, between the flange 68, and terminating in the conical end 71, are axial slots. In these slots are positioned transfer bars 73, 74 whose outer faces are finished flush with the cylinder. At one end these bars are secured in continuations of the slots in the conical end member 71 and at their opposite ends they are attached to a spacer ring 75, surrounding the mandrel 60, between its flanges 68, 69, and over which it is 65 slidable.

Also surrounding the cylinder 66 at the end of the bars 73, 74 and adjacent the flange 68, is an ejector ring 76. This ring is provided with opposite inwardly projecting studs 77, 77 that are secured to another slidable ring 78 surrounding the 75

mandrel 60, between its flange 68 and the ring 75. Secured to the ring 78 and projecting inwardly therefrom, is an actuating stud 79, that passes through an axial slot 80 in the wall of the mandrel, where it enters a short slot 81 formed in the ejector shaft 70. (See Figures 4, 5 and 14.)

When the shaft 70 is moved axially of the mandrel, in a manner presently to be described, it will project the conical end member 11 to the right of the position shown in Figure 4. When the end of the slot 81 engages the stud 79, it will also carry the ejector ring 76 axially of the cylinder 66, toward the right as shown in Figure 4.

As above set forth, the paper is received by the revolving roll 66 during its first complete revolution, and as its trailing edge passes towards this roll, between a lower guide plate 82 and an upper guide plate 83, an adhesive is applied to the under or inner face of its overlapping, seam-forming portion by an adhesive brush 84. This adhesive brush 84 may be of any suitable absorbent material that will, by capillary attraction, convey the adhesive from a container support 85 below it, to the contacted surface of the paper.

The support 85 is essentially an elongated container in whose top face the brush is secured and pivotally suspended by arms 86, 86 from an angle support 87 beneath the plate 82. (See Figure 14.) Connected with one of the arms 86 by a link 88, is a cam follower arm 88^a whose outer end bears on the periphery of a cam 89 and is timed to bring the adhesive brush into contact with the paper as its trailing end passes over the brush. (See Figure 5.)

In order to insure the perfect forming of the paper into a cylindrical form upon the cylinder 66, we have provided co-acting pressure rollers 90 and arcuate guide plates 91 spaced about its periphery. The rollers 90 are covered with a yieldable material such as semi-hard rubber, and each has axial extensions, rotatably received by pivoted bracket members 92 at each end thereof.

As shown in Figure 5, these bracket members 45 are essentially rocker arms pivotally mounted at their centers on radial bosses 93 formed on the cylindrical housing 61 at one end of these rollers. At the other ends of the rollers, the rocker arms 92 are pivotally mounted on bosses 94 circumferentially spaced about the cylinder 66 and provided on the transverse support 12. Projecting outwardly from adjacent bosses 93, and in parallelism, are lever arm extensions 95 of the rocker arms, whose outer ends are connected by link members 96, so that when one rocker arm 92 is rotated to move its respective roller 90 away from the cylinder, all of the rollers will be simultaneously moved. (See Figures 4, 5 and 14.) Beyond its respective roller 90, each rocker arm 92 has an extension 97 between which are secured the arcuate guide plates 91, that, like the rollers 90, are all movable, with the rollers toward or away from the cylinder 66.

Integral with one of the lower rocker arms 92 is a cam follower arm 98, whose lower free end 65 engages a cam 99, rotatable with the shaft 31.

As previously described, during the first revolution of the cylinder 66 or mandrel 60, the strip of paper delivered to it by the gauge and shear 70 rolls 3 and 4, will be formed into a cylinder, with its overlapping edges cemented. During the two subsequent revolutions of the cylinder 66, the co-acting rollers 90 and guide plates 91 by their pressure, will complete the adhesion of the overlapping portions of the paper cylinder. The ends

of this complete cylinder, comprising the first operation, are indicated by dotted lines A in Figure 4 and shown in Figure 15.

In order that the container may be completely sterilized I have provided within the cylinder 66 5 and attached to its walls by countersunk screws, electrical heater units 66^a—66^a encased in a moulded, heat-resisting insulating compound. These units are essentially semi-circular in cross section and are positioned within the cylinder 66 10 below the rollers 90. Current is conducted to the heater units by insulated conductors 66^b—66^b that terminate at collector rings 66^c—66^c on the outer end of the mandrel 60 beyond the end frame 8. Current carrying brushes 66^d—66^d mounted on 15 the latter and connected by wires 66^e—66^e with a source of current (not shown), contact the collector rings 66^c—66^c to complete the circuit. The heated mandrel in contact with the inner cylinder walls, thus renders it sterile. 20

When the cylinder 66 is stationary, due to the action of the intermittent gear 31, the cam 99 will be so timed to actuate the rocker arms 92 to move all of the rollers 90 and guide plates 91 25 away from the cylinder 66.

At this time the ejector shaft 70 will be moved axially and the ejector ring 76 will slide axially along the cylinder 66 and under the now disengaged rolls 90 and guides 91. By this action the paper cylinder previously formed is moved 30 to the right as shown in Figure 4, to bring its one end into position in alignment with the rotary die 11 as indicated by the dotted line B, the opposite end of the now completed paper cylinder being engaged by the ejector ring 76. 35 The ejector ring 76 will now be returned to its position as shown in Figure 4, and a second paper cylinder will be formed simultaneously with the second forming action, later to be described.

The reciprocating movement of the ejector 40 shaft is accomplished by the following means. (See Figures 4 and 5.) Secured to the outer end of the shaft 70 beyond the gear 59 is a yoke member 100, vertically positioned and having attached to its lower end an actuating rod 101, that projects laterally through the transverse member 16, below the mandrel 60. Attached to the inner end of the rod 101 is an apertured slide member 102, slidably positioned on a fixed rod 103. This rod is supported between the end frame 9 and 45 the transverse support 33.

Formed on the top of the member 102 is a roller stud 104, received in the forked end 105 of a cam lever 106. The latter, at its opposite end, is pivotally attached to a boss 107 provided 50 on the rear longitudinal member 24. (See Figure 5.)

Intermediate the ends of lever 106, we have provided on its under side a cam stud 108, received by a cam slot 108^a on the periphery of 60 a drum cam 109 below it. The latter is keyed or otherwise secured to a shaft 110 whose ends are journaled in the end frame 9 and transverse support 33.

By means later to be described, the cam 109 65 is imparted a continuous rotation at the same speed as the shaft 21. Since one paper cylinder is formed upon the cylinder 66 for each revolution of the shaft 21, each revolution of the cam 109 will cause its cam slot 108^a to move the 70 ejector shaft 70 to the right as shown in Figure 4, to transfer the previously completed paper cylinder. The return of the ejector shaft is facilitated by a tension spring 111, between the lever 106 and the end frame 9. 75

When the cylinder 66 comes to rest the seam or adhesive joint will be positioned under the top roller 90, and as the paper cylinder is moved to the right, this seam will be passed under a 5 spring tensioned, knurled roller 112 positioned above the cylinder 66 and whose sharp ridges or teeth will firmly unite the over-lapping edges of the paper cylinder.

The roller 112 is freely mounted in a bracket 10 member 113 and supported from one of the bosses 94 on the support 12 as shown in Figure 4. The forming of the tapering plaited neck and the cap seat, will next be described as the second 15 operation. We wish to point out at this time that this second operation is carried out simultaneously with the performance of the first operation on a succeeding container and the completion of a third operation, later to be described. It is by such progressive steps that faster production 20 is accomplished. Three containers, in various stages are constantly in progress of manufacture.

When the completed paper cylinder above described is transferred to the right, to the dotted line position indicated by the letter "B" in Figure 4, its upper end, surrounding the conical male die 71, will be engaged by a co-acting conical female die 114 similar to the die 71. This die 114, 25 rotatable in synchronism with the die 71, is provided with a like number of circumferentially spaced axial slots 115 which, meshing with the ribs 72, reduce the paper cylinder to a ribbed conical neck, the surplus paper being absorbed in forming the ribs thereon. (See Figures 4, 6 30 and 12.)

The die 114 as shown at Figure 4, has integral with its larger end an axial extension 116 journaled in spaced bearings 117, 117 provided in a swivel bracket 118. Between the bearings there 40 is keyed to the axial extension a helical gear 119 by which the die is rotated. (See Figure 13.)

Adjacent the gear 119 is a vertical shaft 120 at right angles to the axis of the die, and having thereon another gear 121 like the gear 119 and 45 meshing therewith. The shaft 120 is journaled in a bearing formed in the bracket 118 and it also has keyed thereto, and at the lower end thereof, a gear 122.

Integral with the bracket 118 is a boss 123, having therein a vertical aperture 124 in which a short vertical shaft 125 is received and about which the bracket is rotatable. This shaft 125 is journaled in elongated bearings 126 provided on a plate 127, secured between the supports 12 and 50 33, below the mandrel 66. Secured to the vertical shaft 125 between its bearings 124 and 126 is another gear 128 meshing with the gear 122. (See Figures 4 and 13). When the shaft 125 is 55 rotated by a means presently to be described, the female die will be rotated through the gears 122 and 128, and 119 and 121.

It is evident that the bracket 118 is rotatable about the vertical shaft 125 away from and out of engagement with the die 71, to permit the entry 60 of the paper cylinder over the mandrel 66. When the paper cylinder is properly positioned, the female die 114 will be forced into engagement with the die 71 by a timed cam 129 on the shaft 110 and rotatable with it. Formed in the periphery of 65 this cam is a cam slot 130, engaged by a cam roller 131 carried in the outer free end of a lever arm 132 integral with the bracket 118. Upon completion of the neck forming operation, this cam will 70 rotate the female die away from the male die 71. (See Figure 4.)

Rotation is imparted to the vertical shaft 125 by a horizontal shaft 132a, parallel with the mandrel 66, and journaled in bearings provided for it in the end frame 9 and support 12. Secured to the end of the shaft where it projects beyond the support 12 is a spiral gear 133 meshing with a like gear 134 on the upper end of the shaft 125. (See Figures 2, 4 and 13.)

Keyed to the opposite end of the shaft 132a, outside of the end frame is a gear 135 of the same size as the gear 59 with which it meshes. When the gear 59 is rotated to turn the mandrel, it will also rotate the shaft 132a and, with it, the female die 114 to form the tapering plaited neck of the container as the dies are moved into co-acting engagement by the cam 129.

Simultaneously with the formation of the tapering plaited neck of the container as above described, I have provided the following means to finish the neck and to form a cap seat at the end of the neck as shown in Figures 9, 10 and 15. The neck finishing and seat forming operation is accomplished in two stages, first by a neck flanging spinner 136, and finally, by a seat forming spinner 137.

Referring now to Figures 4 and 9, the neck flanging spinner 136 consists of a revolving tubular sleeve 138, having adjacent one end a flange 139 rounded at its outer edge. Beyond the flange the sleeve corners are rounded to form a slightly 30 tapered tenoned end 139a. This sleeve 138 is rotatably mounted in a bearing bushing 140 and is retained against axial movement by a V-pulley 141 secured to the end of it, opposite the flange 139.

The bushing 140 is mounted in the outer free end of a spinner arm 142, whose opposite end terminates in a hub 143. Also extending from the hub 143 is another spinner arm 144 positioned 90 degrees circumferentially from the arm 142, and 40 in whose outer end the seat forming spinner 137 is rotatably mounted in a bearing 145.

As shown in Figure 10 this seat forming spinner comprises a tubular sleeve 146 to one end of which a V-pulley 147 is attached.

At its opposite end the sleeve 146 is provided with a flange 148 that engages the end of the bearing 145 to resist end thrust. Adjacent the flange 148, there is formed within the sleeve an internal flange 149, whose face, opposite the pulley 147, is undercut to effect a semi-circular seat 149a adjacent the inner wall of the sleeve 146.

At its center the hub 143 has an axial bore to receive a sleeve bearing 150. Rotatably mounted within the bearing is a slidble sleeve 151 to one 55 end of which a double V-pulley 152 is attached. At its opposite end the sleeve 151 has a flange which, with the pulley, will retain the hub and bearing upon it.

One face of the hub 143, opposite the pulley 60 152 is turned down to form a shoulder 153 concentric with the bearing and on which a gear 154 is secured. Beyond the gear the shoulder 153 has therein a groove 155, engaged on opposite sides by the forked end 156 of a shifter arm 157.

Formed in the inner wall of the sleeve 151 is a keyway to receive a key 158 rotatable with a spinner drive shaft 159, and over which the sleeve is slidble. The shaft 159, supported in parallelism with the mandrel 66 and in horizontal alignment with it, is journaled in bearings 160 and 161 carried by the support 33 and end frame 18 respectively. (See Figures 1, 4 and 6.)

Below the shaft 159, parallel therewith and likewise rotatable in bearings provided in the sup- 75

port 33 and end frame 18, is a counter shaft 162. Secured to this shaft is a gear 163 of the same diameter as the gear 154, with which it meshes. Keyed to a hub projection on the face of this gear 5 is a slotted spider 164 of a conventional Geneva gear drive.

Co-acting with 90 degree spaced slots 165 formed in the spider 164 is a stud 166 carried by a Geneva gear disc 167 below the spider. This gear 10 disc 167 is keyed to a drive shaft 168, below the shaft 162 and in axial alinement with the shaft 12, likewise journaled in bearings provided for it in the support 33 and end frame 18.

Also mounted on this shaft 168 and against the 15 face of the disc 167, below the spider 164 is a lock plate 169. It is generally understood that when the stud 166 has effected the desired quarter turn of the spider 164, it will pass out of engagement with one of the slots 165 and then the periphery 20 of the lock plate will turn through a circular clearance 170 provided in the periphery of the spider 164 between its spaced radial slots. When one of the circular clearances 170 is so engaged by the lock plate the spider can not be rotated in 25 either direction. Now, as the stud 166 is rotated with the disc 167, it will re-enter a succeeding slot 165 to again rotate the spider and its gear 163, and the spider will rotate through a depression 171 formed in the periphery of the lock plate 30 169. (See Figure 6.)

When the gear 163 and its meshing gear 154 are thus rotated step by step at 90 degree intervals, first the neck-forming spinner 136 and then the seat-forming spinner 137 will be successively 35 presented at the end of the mandrel 66. When the neck-forming spinner is positioned at the end of the mandrel, it will be advanced toward the end of the latter, as the co-acting rotary dies form the tapering neck; and when in full engagement, the female die will form the neck outwardly as shown by the dotted lines in Figure 9.

Due to the revolving spinner, this operation is rapidly accomplished and as this spinner 136 recedes from its advanced position, the Geneva 45 gear will quickly rotate the spinner hub to bring the seat forming spinner 137 into position before the end of the mandrel 66, and it will be advanced to turn down the flange previously formed as indicated in Figure 9 and thus produce the 50 completed cap seat as indicated by the dotted lines in Figure 10. Each of the spinners 136 and 137 is revolved by belts 172—172 passing over a respective V-pulley and one of the grooves of the double V-pulley 152.

55 The endwise movement is effected in timed relation with the positioning of each spinner at the end of the mandrel by the following means. (See Figures 1, 4 and 6.) The shifter arm 157 is rotatably mounted on a vertical shaft 173 journaled 60 in upper and lower rib stiffeners on the support 33. Below the arm 157 there is also secured to the shaft 173 a cam follower arm 174 whose outer end engages a cam surface 175 provided on the face of the disc 167, opposite the stud 166. Also 65 integral with the arm 157 and projecting at right angles therefrom, is a lever arm 176 projecting through an opening in the support 33. Secured to the outer end of this arm is a tension spring 177 whose opposite end is anchored to a stud 70 secured to the support 33.

When the spinners are successively brought 75 into operating position, one of the cam lobes 175 on the constantly rotating disc 167 will engage the cam follower arm to move the spinner against the container neck as previously described. When

the cam lobe passes out of engagement with the cam follower, the spring 177 will cause the spinner to back away from the mandrel prior to indexing.

Rotation of the shafts 159, 162 and 168 is effected by the following means. Keyed or otherwise 5 secured to the end of the shaft 31 adjacent the support 33 is a gear 179 meshing with a pinion 180 secured to the end of an idler shaft 181. This shaft is journaled in a bearing in the support 33 and has secured to its opposite end another gear 10 182 similar to the gear 179. Meshing with this gear is another pinion 183 secured to the shaft 168. By this train of gears, the shaft 168 is rotated at four times the speed of the shaft 31.

Now, for each revolution of the shaft 31 the 15 shaft 162 will also make one complete revolution intermittently, due to the Geneva gear previously described. Mounted on the end of the shaft 181, adjacent the pinion 180 is another gear 184, also meshing with a gear 185 freely mounted on the 20 end of the shaft 162 where it projects through its bearing in the support 33. This gear functions as an idler and meshes with another gear 186 secured to the end of the shaft 159 above. By these gears 184, 185 and 186, the shaft 159 is 25 rotated at high speed and the spinner 136 and 137 at a corresponding high speed.

When the neck and cap seat forming operations, constituting the second stage are thus completed the cap seat forming spinner will be rotated 30 90 degrees and the die 114 will drop back. When these tools are thus cleared, the ejector will move to the right in the manner previously set forth and in this instance the conical male die 71 will carry this completed container body as shown in 35 Figure 16, farther to the right, to the dotted line position indicated at "C" in Figure 4.

When the container is thus transferred for the final operation, to wit, the insertion and crimping of the container bottom, it is received 40 within a sleeve 187. This sleeve is mounted with the mandrel 66 and supported in the end frame 18. (See Figures 3 and 4.)

At its center this sleeve has integral there- 45 with a split clamp member 189 whose adjacent ends are provided with depending apertured lugs 190, 190, that project below the wall of the housing 188. Passing through the lower ends of the lugs 190, 190 is a clamp stud 191 whose enlarged 50 end is formed with a cam face 192 which engages a like face provided on one of the lugs 190.

Attached to the stud 191 is a short lever 193 to whose outer end an actuating rod 194 is connected. (See Figure 1.) When the stud is 55 rotated by the lever 193 and rod 194, the co-acting cam faces on the stud and one of the lugs, will bring the ends of the split clamp members together to restrict its opening, to thus hold securely the container in its deposited position. 60 (See Figures 1 and 4.)

The lateral movement of the rod 194 is effected by the movement of the actuating rod 101 in the following manner. Slidably positioned on the rod 103, between the member 102 and the 65 adjacent end frame 9, is a collar 194^a to which the end of the rod 194 is secured. Attached to the latter and near the opposite end frame 18, is a collar 194^b to which one end of a tension spring 194^c is fastened. The opposite end of 70 this spring is anchored to the end frame 18. (See Figure 4.)

When the actuating rod 101 is moved to the right, as viewed in Figure 4, the member 102 will move along the rod 103, and the spring 194^c 75

will then move the rod 194 also to the right, sliding the collar 194^a along the rod 103 and effecting a release of the container held within the clamp member 189. When the actuating 5 rod is returned to the left, the member 102 will engage the collar 194^a and also move it to the left, effecting a rotation of the clamp stud 191 through the lever arm 193 attached thereto, and thus tightening the clamp member 189 about 10 the unfinished container positioned within the sleeve.

Rearward of the sleeve 187 and likewise positioned in a housing 195 supported in the end frame 18 in this housing 195, we have provided 15 a magazine 196 for the preformed container bottoms, and from which they are fed by spring pressure means. Between the sleeve 187 and the magazine 196 is a horizontal shaft 197 whose ends are journaled in bearings provided for it in 20 the end frame 18 and the support 33.

Freely mounted on the shaft 197 and intermediate its end bearings, is a slidable sleeve 199 rotatable about the shaft. Attached to one end of this sleeve adjacent the support 33 is 25 a gear 200, and to its opposite end, the hub 201 of the bottom transfer and crimping devices is attached. Projecting radially from this hub, and from diametrically opposite sides thereof is a transfer arm 202 and a crimping head 30 arm 203.

Slidably mounted on the sleeve 199 is a collar 204 having integral with one end thereof, spaced flanges to form between them a groove 205. At 35 its other end, studs 206—206 project from opposite sides of the collar 204.

Formed on the outer end of the transfer arm 202 is a boss 207, having therein a flanged bushing 208 as shown in Figure 11, and in axial alignment with the shaft 197. At one end, adjacent the end frame 18, the aperture 209 in the bushing is flared to form a tapering seat for a sliding sleeve 211 positioned within it. Beyond the end of the bushing the sleeve 211 is flanged, and to which a flanged transfer disc 212 is riveted. This disc and one end of the sleeve to which it is attached are split, to form a yieldable structure, which, when the sleeve 211 is drawn into the tapering seat, will constrict the diameter of the disc. (See Figures 4 and 11.)

50 Secured to the opposite end of the sleeve 211 where it projects beyond the opposite face of the boss 207, is a collar 213. This collar is engaged by an actuating arm 214 having spaced fingers 215, 215 which straddle the sleeve between its 55 collar and the boss 207, and a center finger 216 to engage the opposite face of the collar 213 at the end of the sleeve.

Formed on the arm 202 between the boss 207 and its hub 201, is a slotted boss 217 in which 60 the arm 214 is pivotally mounted. At its inner end the arm 214 is forked and provided with oppositely positioned studs 218 that engage in the groove 205. Now, when the transfer arm is positioned before the magazine 196, it will be 65 advanced toward the magazine with the transfer disc 212 contracted. When the arm reaches its advanced position, the actuating arm 214 will force the sleeve 199 out of its tapering seat 210, and the disc 212 will automatically expand to 70 grip the inner face of the flange provided on the pre-formed paper bottoms within the magazine 186.

When the transfer arm 202 backs away from the magazine, it will be intermittently rotated 75 about the shaft 197 to a position before the open

bottom end of the paper container held within the sleeve 187. When so positioned, the transfer will again be advanced to insert the pre-formed bottom within the container, and the actuating arm will draw the sleeve 199 into its 5 tapering seat to release the flanged disc 212 from the container bottom as the transfer arm 202 backs away.

The rotation of the transfer arm 202 and the crimping head arm 203, as well as the movement 10 of the actuating arm 214 is accomplished by the following means. (See Figures 3, 4 and 6.) Keyed to the shaft 168 adjacent the end frame 18 is a helical gear 219 that meshes with another helical gear 220, positioned at right angles with 15 the gear 219 and keyed to a transverse shaft 221. This shaft 221 is positioned at the front of the machine in a bearing 222 supported by the intermediate transverse member 21 of the end frame 18. At its rear end this shaft 221 is journaled in another bearing 223, likewise supported by the member 21. Adjacent the bearing 223 there is attached to the shaft another helical gear 224, and driving a like gear 225 positioned above it, at right angles to the gear 224. The gear 225 20 is keyed to a shaft 226 parallel with the shaft 197 and journaled in the support 33 and end frame 18. (See Figures 3, 4 and 6.)

By these gears the shaft 226 is rotated at the same speed as the shaft 168. Also the shaft 110 30 is rotated at one fourth the speed of the shaft 226 by a pinion 226^a on the shaft 226 and a gear 226^b on the shaft 110. Keyed to the shaft 226 is a drum cam 227, having formed in its periphery substantially parallel cam slots 228 and 229, by 35 which the actuating arm 214 is operated and the hub 201 shifted axially of the shaft 197.

Engaging in the cam slot 228 is a cam lever 230, actuated thereby, and pivotally mounted on a vertical shaft 231 mounted in the support 33. 40 At its opposite end the lever is forked, and its forked ends slotted to receive therein the studs 206, 206 of the sleeve 204. (See Figure 4.)

Engaging the cam slot 229 is another cam lever 232, likewise pivotally mounted on the shaft 231. 45 In a cylindrical boss 233 at the opposite end of the lever 232, we have provided a slotted bushing 234 rotatable in the boss 233. Through the slot in the bushing the gear 200 is free to turn, and by which the gear 200 and its sleeve 199, carrying the hub 201, may be shifted axially. The hub 201 is intermittently rotated to bring, first the transfer head and then the crimping head to position before the sleeve 187.

As previously described the bottom is inserted 55 in the open end of the container by the transfer head and then the hub 201 is again rotated, this time, to position the crimping head before the unfinished bottom and the transfer head before the magazine. The indexing of this hub is accomplished by the gear 200, which meshes with a like gear 235 below it. This gear has a hub extension 236, to whose opposite end another gear 237 is secured. These gears are freely mounted on a stud 238 carried by the support 33. (See 60 Figure 4.)

Meshing with the gear 237 is an idler pinion 238^a carried by a stud 239 and also meshing with the gear 163 on the shaft 162 and by which the shaft 159 is also rotated. (See Figures 4 and 6.) 70 Since the gears 200 and 235, and the gears 237 and 163, are of the same diameter, the spinners 136 and 137, and the transfer and crimping heads, will be rotated in synchronization to alternately position these before the container as it is formed. 75

It should be noted that these respective heads are indexed 90 degrees at one time, and during one quarter of the cycle.

When the arms 202, 203 are positioned vertically and the spinner 136 is below the shaft 159, the space between the mandrel 66 and the sleeve 187 is clear. During this period the actuating arm effects the transfer of the partly finished container from "B" to the sleeve 187.

10 The final operation, to wit, the crimping of the bottom in place will now be described. Formed on the outer end of the arm 203 is a boss 240 provided with an aperture parallel with the shaft 197. Positioned in the aperture is a bushing 241, in which there is rotatably mounted a sleeve 242. Secured to one end of this sleeve is a spider 243, and to its opposite end, a collar 244 by which the sleeve is retained within the bushing 241. (See Figures 4, 7 and 8.)

20 Rotatably positioned within the sleeve 242 is the hollow shaft 244^a of a gear 245, positioned against the face of the spider 243. At the end of the shaft, opposite the gear, there are opposite, inwardly projecting pins 246, 246 received in double spiral grooves 247, 247 formed on an actuating rod 248, slidable within the shaft 244. The rod is prevented from rotating by a key 249 projecting inwardly from the sleeve 242 into an axial keyway 250 provided in the enlarged outer 25 end of the rod 244. Beyond the end of the sleeve the rod is provided with a reduced neck portion 251, that is engaged by an actuating lever 252, and by which it is moved axially to rotate the gear 245 in opposite directions. (See Figures 7 30 and 8.) The lever 252, like the arm 214, is pivotally connected at its center to a boss 253 formed on the arm 203. At its opposite end the arm is forked to engage the groove 205 on the sleeve 204.

Formed in the spider 243, in axial alignment 40 with the sleeve 242, are four apertures 254 spaced 90 degrees circumferentially about its center. Rotatably mounted within each aperture 254 is the reduced end of an eccentric shaft 255, having an enlarged outer end 256 eccentric with it. Between the enlarged and reduced ends of each shaft 255 we have provided a D shaped shoulder 257 slightly larger than the shaft 255 and concentric therewith. Positioned upon the shoulder 257 of each shaft is a gear 258 that meshes with the gear 245.

Positioned upon the enlarged end of two of the diametrically opposite shafts are knurled rollers 259, 259. These rollers have at their outer ends a flange 260 as shown in Figure 8. Beyond each 55 of these opposite shafts 255 there is provided in the spider another aperture in which an outer shaft 261 is rotatable. These shafts are in all respects like the shafts 255 and have freely mounted on their outer ends rollers 262, 262. Formed at the outer end of each roller 262 is a wide flange 263, reduced at its outer face to to 60 form a stepped shoulder 264. Between the roller and the spider, each of these shafts has thereon a gear 265 that meshes with a respective gear 258 65 carried by a respective inner shaft 255.

When the shafts 255 and 261 are rotated in unison by the center gear 245, the eccentric outer ends will move their respective rollers 259 and 262, either together to form the engaged flanges 70 of the paper container and its bottom at right angles to its sides, or move them apart as shown in Figure 8.

Freely mounted on the eccentric shoulders 256 of the shafts 255 intermediate those carrying the 75 rollers 259, are rollers 265. These rollers have

near their outer ends, flanges 266, which co-act with the inner faces of flanges 267 that are provided at the outer ends of adjacent form rollers 268. These rollers 268, like the previous rollers, are rotatably mounted on eccentric shoulders 269 5 provided at the outer ends of shafts 270. These shafts 270 are similar to the shafts 255, being freely mounted in apertures formed in the spider 243 beyond the inner shafts 255.

Positioned on each shaft 270 is a gear 271 that 10 meshes with the gear 258 provided for the adjacent shafts 255, 255, which gears also mesh with the center gear 245. When the gear 245 is rotated, the gears 271 and 258 will rotate their respective eccentric shafts 255, 255 and 270, 270 15 to bring their respective rollers 265, 265 and 268, 268 together or apart, depending on the rotation of the gear 245. When these rollers are brought together, they will form the right angle, flanged bottom seam inwardly, and firmly crimp these 20 edges together to complete the seaming operation. These rollers are shown together in Figure 8.

When the actuating rod 248 is partly withdrawn from the hollow shaft 244, its spiral 25 grooves will rotate the various form rollers until all of them are disengaged as the spider 243 is advanced against the inserted bottom positioned within the container cylinder. When the spider 30 is fully advanced, the cam slot 228, through the levers 230 and 252, will withdraw the actuating rod 248 to its extreme outer position and thus bring the rollers 259, 259 and 262, 262 together to perform the first seaming operation on the 35 container bottom. Also the transfer disc will be inserted in the container bottom in the magazine 196, but contracted out of engagement with the bottom.

When the first seaming operation is completed, 40 the actuating rod 248 is forced inwardly to rotate the gear 245 in a reverse direction. The rollers 259, 259 and 262, 262 will now be separated, and the other rollers 265, 265 and 268, 268 will be brought together as previously described to complete the seaming operation. The transfer disc, 45 which is still inserted in the container bottom in the magazine will now be expanded to grip it.

Upon completion of the last seaming operation, to produce the container as shown in Figure 17, the actuating rod 248 will be partly withdrawn 50 again to release all of the forming rollers carried by the spider. The cam 229 will now move the hub 201 axially, and with it, the crimping head and the transfer head away from the sleeve and the magazine prior to indexing. (See Figures 4, 55 6, 7 and 8.)

While the various forming rollers are engaged in the crimping operations, the spider 243 is rotated by the following means to carry the crimping rollers around the wall of the paper container. Formed on the periphery of the spider 243, is a gear 273 that meshes with a similar gear 274 keyed to the shaft 197 by which it is rotated. (See Figures 4, 7 and 8.)

Secured to the outer end of the shaft 197 beyond the end frame 18 is a gear 275. This gear meshes with an idler pinion 276, rotatable on a stud 277 carried by the end frame 18. Meshing with this pinion is a larger gear 278 having attached to its outer face a pinion 279. This gear 278 and pinion 279 are also rotatable above a stud 280 secured to the outer face of the end frame. The pinion 279 is rotated by a larger gear 281, keyed to the outer end of the shaft 226 beyond its 75

bearing in the end frame. (See Figures 3 and 4.)

Following the bottom seaming operation, the clamp member 189 is released, as previously described, and as the ejector moves to the left, the 5 end of the die 71, carried thereby, will engage the bottom of the completed container and force it out of the sleeve 187. When thus ejected, the completed container may be conveyed through closed tubes or chutes 282 indicated by the dotted 10 line in Figure 4. These tubes may be used to deliver the completed container to a bottle filling and capping machine as ordinarily used by the milk bottling industry, thus rendering it unnecessary to handle them. Also if desired, these 15 livery tubes may also divert the completed containers to storage means for future use.

The process or operations involved in the manufacture of a single container are as follows. The paper from the supply roll (not shown) is 20 continuously drawn into the machine by the feed rolls 1 and 2, which delivers it to the gage and shear rolls 3 and 4 behind them. These rolls 3 and 4 rotate intermittently to make one complete revolution to advance and sever a strip of paper 25 sufficient to form the container cylinder with an overlapping longitudinal seam. As the paper is thus advanced by these latter rolls 3 and 4, it passes between upper and lower guide plates to a mandrel 60, and as the trailing edge of the sheet 30 passes between these plates, an adhesive is applied to it to form a liquid-tight longitudinal seam.

The mandrel 60 is likewise intermittently operated, starting simultaneously with the rolls 3 and 4 to receive the paper advanced by them. 35 However, after the adhesive coated edge passes to the mandrel, the latter makes two complete revolutions, to perfect, under the pressure rolls 90 and guide shoes 91, the longitudinal seam.

After the mandrel 60 comes to rest the pressure 40 rolls 90 and shoes 91 are moved out of contact with it by the cam 99. When the mandrel 60 is thus disengaged the cam 109, rotating in timed relation with the mandrel, will move the ejector 45 shaft 70 to the right, whereupon the ejector ring 76 will move the completed paper cylinder, shown in Figure 15, to the right to the position indicated by the dotted line B in Figure 4. As the paper cylinder is moved along the mandrel 60, its longitudinal seam will pass under the spring tensioned 50 knurled roller 122, which further compresses it.

For the purpose of sterilizing the container, the electric heater units 66^a—66^a will maintain the mandrel at a sufficiently high temperature to destroy all bacteria upon the surface of the paper 55 during the time that the cylinder is being formed.

After the paper cylinder is moved to the position B, the ejector ring 76 will be returned to its normal position and the cam 129 will bring the dies 114 and 71 into co-operative engagement 60 when the mandrel 60 and the cylinder upon it are again rotated, to form the tapering plaited neck of the container. While the die 114 is advancing to form the neck of the container, the spinner 136 65 will be moved against the end of the die 71 to perform the flanging operation on the end of the container. As soon as this first neck operation is finished, the cams 175 will cause the spinner 136 to retreat and the Geneva gear mechanism to bring the second spinner 137 before the die 71 to 70 turn down the flange to form a cap seat on the container, leaving it in the form shown in Figures 16 and 17.

With the completion of the forming of the plaited neck and the cap seat, the hub 143, carrying the spinner arms, will rotate the latter to a

vertical position and the mandrel 60 will again come to rest. When the rotation of the mandrel has ceased, the ejector shaft 70 carrying the die 71 will again move to the right, the die 71 this time conveying the now-completed paper cylinder to its extreme right-hand position, as indicated by the dotted lines C in Figure 4, within the sleeve 187.

The withdrawing die 71 will leave the cylinder 10 within the sleeve 187. When the ejector shaft 10 has reached its normal position, the slide member 102 will force the collar 194^a toward the left and thus lock the paper cylinder within the sleeve 187, ready to receive the container bottom.

The transfer head shown in Figure 11, while 15 contracted, will enter the magazine 196, where, when expanded, it will grip one of the flanged container bottoms therein. This transfer head then drops back, through the action of its cam 229, and by the same Geneva gear before referred to, it is 20 revolved to a position before the end of the sleeve 187. The transfer head is again advanced to deposit the container bottom within the open end of the paper cylinder at its position C indicated in Figure 4. When thus deposited, the transfer head will be contracted by the cam 228 and again withdrawn by the cam 229. The crimping head 25 will now be rotated to operative position at the end of the sleeve 187 and advanced against the container bottom.

When this crimping head is rotated by the gear 30 214, the rolls 259 and 262 will co-act to perform the first operation, and when they are disengaged, the form rolls 265, 268 will be moved together to 35 complete the bottom crimping action.

The hub 201 is now rotated to place the transfer arm and crimping head arms out of position before the sleeve 187. This operation is simultaneous with the indexing of the spinner heads, 136, 137, thus permitting an unobstructed travel 40 for the ejector shaft and the die 71 carried thereby.

When the ejector shaft 70 is again advanced, the unfinished container carried thereby will engage the bottom of the completed container 45 to force it out of the sleeve.

From the foregoing detailed description, it is evident that we have produced efficient and compact means for forming liquid-tight containers in a continuous manner by coordinated steps, 50 said containers, excepting the pre-formed bottoms being manufactured from a roll of paper fed into the device.

In Figure 18, we have disclosed a multiple machine in which we propose to manufacture simultaneously containers in three different sizes, such as quarts, pints and half-pints. This machine comprises a series of container producing units 55 as disclosed in Figures 1 to 14 inclusive, and designated herein as a quart bottle producing unit 60 283, positioned in the base of the device. Positioned above the unit 283 and connected to the frame thereof is a pint bottle producing unit 284. Above this unit we have shown a smaller unit 285 for the production of half-pint containers. For the purpose of clarity, a detailed description of each unit will be omitted, their operation being in all respects like the single unit 65 previously described.

In Figure 18 we have shown a delivery tube or chute 286, 287 and 288 for each unit 283, 284 and 285, respectively. Adjacent the machine these delivery tubes are formed to a common delivery chute 289 through which a selected one of the va- 75

rious sizes being produced may be delivered to a desired destination. The bottles within the chutes are propelled by each succeeding container ejected by the ejector means previously described.

5. With the above-described multiple machine a saving in floor space as well as speedier production is readily effected.

Having described our invention, we claim:

1. In a machine for making paper containers, a 10 pair of friction rollers adapted to advance and sever from a sheet of paper material a unit of the desired size, a horizontally disposed mandrel to receive and form the severed unit into a cylinder having overlapping longitudinal ends, reciprocated adhesive means for periodically applying adhesive to the one end of said sheets, pressure means for connecting said ends into a longitudinal seam, and rotatable means for applying a bottom to said cylinder, after it leaves the mandrel.

2. In a machine for making paper containers, a pair of friction rollers adapted to advance and sever from a sheet of paper material, a unit of the desired size, a horizontally disposed mandrel supported at one end to receive and form the severed unit into a cylinder having overlapping ends, reciprocated adhesive means for periodically applying adhesive to the one end of said sheets, pressure means for connecting said ends into a longitudinal seam, a bottom applying device at the free end of the mandrel, and means for advancing the formed cylinder along the mandrel, and from the mandrel horizontally to the bottom applying device.

3. In a machine for making paper containers, a pair of friction rollers adapted to advance and sever from a sheet of paper material a unit of the desired size, a horizontally disposed mandrel supported at one end to receive and form the severed unit into a cylinder having overlapping ends, reciprocated adhesive means for periodically applying adhesive to the one end of said sheets, pressure means for connecting said ends into a longitudinal seam, a stationary bottle receiving member, a bottom applying device between the free end of the mandrel and the bottle receiving member, neck plaiting means between the mandrel and the bottom applying device, and means for advancing the formed paper cylinder on the mandrel to the neck plaiting means, and then horizontally into the bottle receiving member for engagement by the bottom applying device.

4. In a machine for making paper containers, a pair of friction rollers adapted to advance and sever from a sheet of paper material a unit of the desired size, a horizontally disposed mandrel supported at one end to receive and form the severed unit into a cylinder having overlapping ends, reciprocated adhesive means for periodically applying adhesive to the one end of said sheets, pressure means for connecting said ends into a longitudinal seam, revolving conical neck plaiting dies to receive the neck portion of the formed cylinder to plait it, a stationary bottle receiving member and a reciprocating device for shifting the formed cylinder to the stationary bottle receiving member away from the mandrel and simultaneously advancing a succeeding cylinder to a plaiting position on it.

5. In a machine for making paper containers, a pair of friction rollers adapted to advance and sever from a sheet of paper material a unit of the desired size, a horizontally disposed mandrel supported at one end to receive and form the severed unit into a cylinder having overlapping

ends, reciprocated adhesive means for periodically applying adhesive to the one end of said sheets, pressure means for connecting said ends into a longitudinal seam, revolving conical neck plaiting dies to receive the neck portion of the formed cylinder to plait it, a stationary bottle receiving member, a reciprocating device, means for actuating said reciprocating device to shift said formed cylinder to the stationary bottle receiving member away from the mandrel and to simultaneously advance a succeeding cylinder to a plaiting position upon it, and means for reversing the movement of said reciprocating device to withdraw the die from the advanced cylinder and force it into the neck portion of the succeeding cylinder to be plaited.

6. In a machine for making paper containers, a pair of friction rollers for continuously feeding forward a sheet of material, a second pair of friction rollers adapted to receive the moving sheet from the first rollers, to intermittently advance and sever therefrom a unit of the desired size, a horizontally disposed mandrel, to receive and form the severed unit into a cylinder having overlapping longitudinal ends, reciprocated adhesive means for periodically applying adhesive to the one end of said sheets, pressure means for connecting said ends into a longitudinal seam, a stationary bottle receiving member, a device for ejecting the formed cylinder from the mandrel, and means for applying a bottom to said cylinder after it is received in the stationary bottle receiving member.

7. In a machine for making paper containers, a pair of friction rollers adapted to intermittently advance, and sever from a sheet of paper material a unit of the desired size, a horizontal mandrel supported at one end, to receive and form the severed unit into a cylinder having overlapping longitudinal ends, reciprocated adhesive means for periodically applying adhesive to the one end of said sheets, pressure means for connecting said ends into a longitudinal seam, means for laterally ejecting the formed cylinder in stages from the free end of the mandrel, a stationary bottle receiving member and means for applying a bottom to said cylinder after it is received by the stationary bottle receiving member.

8. In a machine for making paper containers, a pair of friction rollers adapted to intermittently advance, and sever from a sheet of paper material a unit of the desired size, a horizontal mandrel supported at one end to receive and form the severed unit into a cylinder having overlapping longitudinal ends, reciprocated adhesive means for periodically applying adhesive to the one end of said sheets, pressure means for connecting said ends into a longitudinal seam, an ejector shaft longitudinally movable through the mandrel, and an ejector ring connected to said shaft for longitudinal movement thereby over the mandrel to shift the formed cylinder to an advanced position thereon.

9. In a machine for making paper containers, a pair of friction rollers adapted to intermittently advance, and sever from a unit of the desired size, a horizontal mandrel supported at one end to receive and form the severed unit into a cylinder having overlapping ends, reciprocated adhesive means for periodically applying adhesive to the one end of said sheets, pressure means for connecting said ends into a longitudinal seam, an ejector shaft longitudinally movable through the mandrel, said mandrel being formed with two axial slots, radial stud means on said shaft for longitudinal movement through said slots, and an

ejector ring secured to the outer ends of the stud means for longitudinal movement thereby over the mandrel to shift the formed cylinder to an advanced position thereon when the shaft is imparted an axial movement in that direction.

5 10. In a machine for making paper containers, a pair of friction rollers adapted to intermittently advance, and sever from a unit of the desired size, a horizontal mandrel supported at one end to receive and form the severed unit into a cylinder having overlapping ends, reciprocated adhesive means for periodically applying adhesive to the one end of said sheets, pressure means for connecting said ends into a longitudinal seam, an integral hub for the mandrel, aligned axial slots formed in the outer shell and hub, an ejector shaft longitudinally movable through said hub, studs projecting radially from said shaft for longitudinal movement through said slots, and an 15 ejector ring secured to the outer ends of the studs for longitudinal movement thereby over the mandrel to shift the formed cylinder to an advanced position thereon when the shaft is imparted an axial movement in that direction.

20 11. In a machine for making paper containers, a pair of friction rollers for advancing and severing from a sheet of paper material a unit of the desired size, a horizontal mandrel to receive and form the severed unit into a cylinder having overlapping longitudinal edges, reciprocated adhesive means for periodically applying adhesive to the one end of said sheets, pressure means for connecting said ends into a longitudinal seam, means for intermittently rotating the friction rollers and the mandrel, a device included in the latter means for periodically stopping the rotation of the mandrel, a shaft longitudinally movable through the mandrel, and an ejector ring connected to said shaft for longitudinal movement thereby over the mandrel to shift 25 the formed cylinder to an advanced position on the mandrel when the rotation thereof has been halted.

30 12. In a machine for making paper containers, a pair of friction rollers for intermittently advancing and severing from a sheet of material a unit of the desired size, a horizontal mandrel supported at one end to receive and form the severed unit into a cylinder having overlapping ends, reciprocated adhesive means for periodically applying adhesive to the one end of said sheets, pressure means for connecting said ends into a longitudinal seam, and co-acting rotary forming means on the free end of the mandrel to receive, and plait the neck of, the connected 35 paper cylinder during the rotation of the mandrel.

40 13. In a machine for making paper containers, a pair of friction rollers for intermittently advancing and severing from a sheet of material a unit of the desired size, a horizontal mandrel supported at one end to receive and form the severed unit into a cylinder having overlapping ends, reciprocated adhesive means for periodically applying adhesive to the one end of said sheets, pressure means for connecting said ends into a longitudinal seam, a co-acting rotary die on the free end of the mandrel to receive the connected paper cylinder, and a second rotary die co-acting with the first die to plait the neck 45 portion of the paper cylinder during the rotation of the mandrel.

45 14. In a machine for making paper containers, a pair of friction rollers for intermittently advancing and severing from a sheet of paper material a unit of the desired size, a horizontal hol-

5 low mandrel supported at one end behind the rollers to receive and form the severed unit into a cylinder having overlapping ends, reciprocated adhesive means for periodically applying adhesive to the one end of said sheets, pressure means for connecting said ends into a longitudinal seam, an ejector shaft longitudinally movable through the mandrel, a rotary die on said shaft beyond the free end of the mandrel, means actuated by the ejector shaft to shift the formed paper cylinder to an advanced position on the mandrel, with its neck portion over the rotary die, and a second rotary die co-acting with the first die to plait the neck portion of said paper cylinder.

10 15. In a machine for making paper containers, a pair of friction rollers for intermittently advancing and severing from a sheet of paper material a unit of the desired size, a horizontal hollow mandrel supported at one end behind the rollers to receive and form the severed unit into a cylinder having overlapping ends, reciprocated adhesive means for periodically applying adhesive to the one end of said sheets, pressure means for connecting said ends into a longitudinal seam, an ejector shaft longitudinally movable through the mandrel, a ribbed conical die on said shaft beyond the free end of the mandrel, means actuated by the ejector shaft to shift the formed paper cylinder to an advanced position on the mandrel, with its neck portion over the rotary die, and a conical female die co-acting with the first die to plait the neck portion of said paper cylinder.

the longitudinal free ends of said cylinder, a hub for said mandrel, said hub and the outer wall of the mandrel being formed with aligned slots, an ejector shaft longitudinally movable through said hub, a plaiting die on the ejector shaft beyond the free end of the mandrel, studs projecting from said ejector shaft through the aligned slots, and an ejector ring secured to the outer ends of the studs for longitudinal movement thereby over the mandrel to shift the formed cylinder to an advanced position wherein its neck portion will be over the plaiting die.

19. In a machine for making paper containers, a hollow mandrel horizontally supported at one end to receive and form a sheet of paper material into a cylinder, reciprocated adhesive means for periodically applying adhesive to the one end of said sheets, pressure means for connecting the longitudinal free ends of said cylinder, a hub for said mandrel, said hub and the outer wall of the mandrel being formed with aligned slots, an ejector shaft longitudinally movable through said hub, a plaiting die on the ejector shaft beyond the free end of the mandrel, studs projecting from said ejector shaft through the aligned slots, an ejector ring secured to the outer ends of the studs for longitudinal movement thereby over the mandrel to shift the formed cylinder to an advanced position wherein its neck portion will be over the plaiting die, and arms projecting from the plaiting die longitudinally into the axial slots in the wall of the mandrel, to clear said slots for the advancing studs when the shaft moves outwardly, and to close said slots when the movement of the shaft is reversed.

20. In a machine for making paper containers, a hollow mandrel horizontally supported at one end to receive and form a sheet of paper material into a cylinder, reciprocated adhesive means for periodically applying adhesive to the one end of said sheets, pressure means for connecting the free longitudinal ends of said cylinder, an ejector shaft longitudinally movable through the mandrel, a conical plaiting die carried by said shaft, means actuated by said shaft to advance the formed paper cylinder to a position with its neck portion over the plaiting die, and cam means for reciprocating said ejector shaft, first to move it forwardly to advance the die, the neck-formed paper cylinder on it and the succeeding paper cylinder and then to effect a reverse movement of the shaft to draw the die into the neck portion of the succeeding cylinder.

21. In a machine for making paper containers, a hollow mandrel horizontally supported at one end to receive and form a sheet of paper material into a cylinder, reciprocated adhesive means for periodically applying adhesive to the one end of said sheets, pressure means for connecting the free longitudinal ends of said cylinder, an ejector shaft longitudinally movable through the mandrel, a conical plaiting die carried by said shaft, means actuated by said shaft to advance the formed paper cylinder to a position wherein its neck portion will be over the plaiting cylinder, a conical die co-acting with the plaiting cylinder to plait the neck of the cylinder, and cam means for reciprocating said ejector shaft and the second die, first to withdraw the latter from plaiting engagement with the neck portion of the cylinder, and then to move the shaft forwardly to carry the first die and the neck-plaited cylinder to an advanced position.

22. In a machine for making paper containers, a hollow mandrel horizontally supported at one

end to receive and form a sheet of paper material into a cylinder, reciprocated adhesive means for periodically applying adhesive to the one end of said sheets, pressure means for connecting the free longitudinal ends of said cylinder, an ejector shaft longitudinally movable through the mandrel, a conical plaiting die carried by said shaft, means actuated by said shaft to advance the formed paper cylinder to a position wherein its neck portion will be over the plaiting cylinder, a conical die co-acting with the plaiting cylinder to plait the neck of the cylinder, and synchronized cams for reciprocating said ejector shaft and the second die, first to withdraw the latter from plaiting engagement with the neck portion of the cylinder, then to move the shaft forwardly to carry the first die, the neck-formed cylinder on it, and the succeeding cylinder to an advanced position, then to effect a reverse movement of the shaft to draw the first die into the neck portion of the succeeding cylinder and then to engage the second die with the first die.

23. In a machine for making paper containers, a hollow mandrel horizontally supported at one end to receive and form a sheet of paper material into a cylinder, reciprocated adhesive means for periodically applying adhesive to the one end of said sheets, pressure means for connecting the free longitudinal ends of said cylinder, an ejector shaft longitudinally movable through the mandrel, a conical plaiting die carried by said shaft, means actuated by said shaft to advance the formed paper cylinder to a position wherein its neck portion will be over the plaiting cylinder, a conical die co-acting with the plaiting cylinder to plait the neck of the container, a cam shaft, a cam on said cam shaft for reciprocating the ejector shaft, and a second cam on said cam shaft, and synchronized with the first cam, to reciprocate the second die for the purpose specified.

24. In a machine for making paper containers, a mandrel horizontally supported at one end to receive and form a sheet of paper material into a cylinder, reciprocated adhesive means for periodically applying adhesive to the one end of said sheets, pressure means for connecting the free longitudinal ends of said cylinder, a neck plaiting die at the free end of the mandrel, means for advancing the paper cylinder to a position wherein its neck portion is over the die, a second die co-acting with the first die to plait the neck portion of the cylinder, and a neck flanging spinner adapted to co-act with said dies to flange the neck portion of the container during the plaiting operation.

25. In a machine for making paper containers, a mandrel horizontally supported at one end to form a sheet of paper material into a cylinder, reciprocated adhesive means for periodically applying adhesive to the one end of said sheets, pressure means for connecting the free longitudinal ends of said cylinder, a conical neck plaiting die at the free end of the mandrel, means for advancing the paper cylinder to a position wherein its neck portion is over the die, a second conical die co-acting with the first die to plait the neck portion of the cylinder, and a flanged spinner adapted to be moved against the first conical die to co-operate with the second die in flanging the neck portion of the container during the plaiting operation.

26. In a machine for making paper containers, a mandrel horizontally supported at one end to form a sheet of paper material into a cylinder,

- reciprocated adhesive means for periodically applying adhesive to the one end of said sheets, pressure means for connecting the free longitudinal ends of said cylinder, a conical neck plaiting die at the free end of the mandrel, means for advancing the paper cylinder to a position wherein its neck portion is over the die, a second conical die co-acting with the first die to plait the neck portion of the cylinder, a flanged spinner 5 adapted to be moved against the first die to co-operate with the second die in forming a flange on the neck portion of the container during the plaiting operation, means for withdrawing the flanged spinner, a seat forming spinner, and 10 15 means for advancing the seat forming spinner to the first die to turn down said flange to form a cap seat on the container.
27. In a machine for making paper containers, a mandrel horizontally supported at one end to 20 form a sheet of paper material into a cylinder, reciprocated adhesive means for periodically applying adhesive to the one end of said sheets, pressure means for connecting the free longitudinal ends of said cylinder, a conical neck plaiting die at the free end of the mandrel, means for advancing the paper cylinder to a position wherein its neck portion is over the die, a second conical die co-acting with the first die to plait 25 the neck portion of the cylinder, a shaft, a hub 30 rotatable on said shaft, spaced radial arms on said hub, a spinner on one arm to co-operate with the second die in forming a flange on the neck of the container, and a spinner on the other arm to turn down said flange to form a cap seat, and 35 intermittent means for rotating said hub to bring the first spinner in engagement with the neck portion of the container for the flanging operation, and then to withdraw that spinner and bring the second spinner into engagement with the 40 neck portion of the container for the cap-seating operation.
28. In a machine for making paper containers, a mandrel horizontally supported at one end to 45 form a sheet of paper material into a cylinder, reciprocated adhesive means for periodically applying adhesive to the one end of said sheets, pressure means for connecting the free longitudinal ends of said cylinder, a conical neck plaiting die at the free end of the mandrel, means 50 for advancing the paper cylinder to a position wherein its neck portion is over the die, a second conical die co-acting with the first die to plait the neck portion of the cylinder, means co-acting with said dies to form a cap seat on the plaited 55 neck portion of the container, a horizontal fixed sleeve into which the formed container is adapted to be moved by the paper cylinder advancing means, and means for applying a bottom to said container while it is held by said sleeve.
- 60 29. In a machine for making paper containers, a mandrel horizontally supported at one end to 65 form a sheet of paper material into a cylinder, reciprocated adhesive means for periodically applying adhesive to the one end of said sheets, pressure means for connecting the free longitudinal ends of said cylinder, a conical neck plaiting die at the free end of the mandrel, means for advancing the paper cylinder to a position 70 wherein its neck portion is over the die, a second conical die co-acting with the first die to plait the neck portion of the cylinder, a horizontal fixed sleeve to receive the formed cylinder, said cylinder advancing means adapted to force the formed cylinder within said sleeve, and a clamping device actuated by the withdrawal of the 75

cylinder advancing means to hold the formed cylinder in said sleeve for a bottom applying operation.

30. In a machine for making paper containers, a mandrel horizontally supported at one end to 5 form a sheet of paper material into a cylinder, reciprocated adhesive means for periodically applying adhesive to the one end of said sheets, pressure means for connecting the free longitudinal ends of said cylinder, a shaft reciprocable 10 through said mandrel, a conical plaiting die secured to said shaft, a split sleeve fixedly supported beyond the plaiting die to receive within it the formed cylinder, said shaft adapted to move the die forwardly to carry the formed cylinder into 15 the sleeve, and clamping means surrounding the sleeve and operable by the shaft when withdrawn from the sleeve, to tightly clamp the paper cylinder 20 therein for a bottom applying operation.

31. In a machine for making paper containers, 20 a horizontally supported mandrel to form a sheet of paper material into a cylinder, reciprocated adhesive means for periodically applying adhesive to the one end of said sheets, pressure means for uniting the free longitudinal ends of said cylinder, a horizontal sleeve, means for transferring the formed paper cylinder to the interior of said sleeve, a bottom containing magazine horizontally supported adjacent the sleeve, a horizontal shaft between the sleeve and the magazine, a rotatable transfer arm on said shaft, a head carried by said transfer arm to withdraw a bottom from 25 said magazine and to deposit it within said sleeve, after said head has been rotated to a position before said sleeve, and a crimping head carried 30 by said shaft for rotation to a position to crimp said bottom on the container within the sleeve after the transfer head has been rotated from the sleeve to a position before the magazine.

32. In a machine for making paper containers, 40 a horizontally disposed mandrel to form a sheet of paper material into a cylinder, reciprocated adhesive means for periodically applying adhesive to the one end of said sheets, pressure means for uniting the free longitudinal ends of 45 said cylinder, a horizontally fixed sleeve means for transferring the formed paper cylinder to the interior of said sleeve, a bottom-containing magazine horizontally supported adjacent the sleeve, a horizontal shaft between the sleeve and the magazine, a rotatable transfer arm secured on said shaft, a reciprocable and expansible device carried by said transfer arm for entrance into a bottom in the magazine to withdraw it 50 therefrom and to deposit it within said sleeve after the arm has been rotated to a position before said sleeve, a second arm secured to said shaft, and a crimping head carried by the second arm for rotation to a position to crimp said bottom on the container within the sleeve after 55 the expansible device has been rotated from the sleeve to a position before the magazine.

33. In a machine for making paper containers, 60 a horizontally supported mandrel to form a sheet of paper material into a cylinder, reciprocated adhesive means for periodically applying adhesive to the one end of said sheets, pressure means for uniting the free longitudinal ends of 65 said cylinder, a horizontal fixed sleeve, means for transferring the formed paper cylinder to the 70 interior of said sleeve, a bottom-containing magazine horizontally supported adjacent the sleeve, a horizontal shaft between the sleeve and the magazine, a slidable sleeve rotatable about said shaft, gear means for rotating the slidable sleeve, 75

5 a hub attached to the latter, a transfer arm and a crimping arm projecting diametrically from opposite sides of said hub, an expandible head carried by the transfer arm for withdrawing a bottom from said magazine and for depositing it within the sleeve after said head has been rotated by the transfer arm to a position before the sleeve, and a crimping head carried by the crimping arm for rotation to a position to crimp 10 said bottom on the container within the sleeve after the transfer head has been rotated from the sleeve to a position before the magazine.

34. In a machine for making paper containers, a horizontally supported mandrel to form 15 a sheet of paper material into a cylinder, reciprocated adhesive means for periodically applying adhesive to the one end of said sheets, pressure means for uniting the free longitudinal ends of said cylinder, a horizontal fixed sleeve, means 20 for transferring the formed paper cylinder, to the interior of said sleeve, a bottom-containing magazine horizontally supported adjacent the sleeve, a horizontal shaft between the sleeve and the magazine, a slideable sleeve rotatable around 25 said shaft, gear means for rotating the slideable sleeve, a hub attached to the latter, a transfer arm and a crimping arm projecting diametrically from opposite sides of said hub, cam means to reciprocate the hub axially of the shaft, an 30 expandible head carried by the transfer arm for entrance into the magazine when the hub is shifted toward the latter, and for withdrawal therefrom with a bottom when the hub is shifted in the reverse direction, said slideable sleeve adapted to 35 be rotated by the gear means to bring the transfer head before the fixed sleeve, whereupon the said bottom will be deposited in the fixed sleeve when the hub is shifted toward it, and a crimping head carried by the crimping arm to crimp 40 said bottom to the container after the transfer head has been rotated away from the fixed sleeve and the hub has again been moved axially toward it.

35. A device for applying a flanged bottom to 45 a cylindrical paper container held against longitudinal movement, a shaft, a slideable sleeve on said shaft, a radial arm secured to said sleeve, a spider journaled in the outer end of said arm, means for rotating the spider, two radially spaced 50 pairs of eccentric shafts journaled in diametrically opposite sides of said spider, flanged rollers on said eccentric shafts to partially crimp the flanged bottom to said container when said eccentric shafts are rotated, two pairs of eccentric 55 shafts diametrically journaled in said spider intermediate the first pairs of shafts, and flanged rollers on the intermediate pairs of eccentric shafts to complete said bottom crimping operation when said intermediate pairs of eccentric 60 shafts are rotated.

36. A device for applying a flanged bottom to a cylindrical paper container held against longitudinal movement, a shaft, a slideable sleeve on 65 said shaft, a radial arm secured to said sleeve, a spider journaled in the outer end of said arm, teeth on the periphery of said spider, a gear on said shaft meshing with the teeth on the spider to rotate the latter, two radially spaced pairs of eccentric shafts journaled in diametrically opposite 70 sides of said spider, flanged rollers on said eccentric shafts to partially crimp the flanged bottom to said container when said eccentric shafts are rotated, two pairs of eccentric shafts 75 diametrically journaled in said spider intermediate the first pairs of shafts, and flanged rollers

ers on the intermediate pairs of eccentric shafts to complete said bottom crimping operation when said intermediate pairs of eccentric shafts are rotated.

37. A device for applying a flanged bottom to 5 a cylindrical paper container, held against longitudinal movement, a shaft, a slideable sleeve on said shaft, a radial arm secured to said sleeve, a spider journaled in the outer end of said arm, means for rotating the spider, two radially spaced 10 pairs of eccentric shafts journaled in diametrically opposite sides of said spider, flanged rollers on said eccentric shafts to partially crimp the flanged bottom to said container when said eccentric shafts are rotated, two pairs of eccentric 15 shafts diametrically journaled in said spider, intermediate the first pairs of shafts, flanged rollers on the intermediate pairs of eccentric shafts to complete said bottom crimping operations, mating gears on the pairs of eccentric shafts, a 20 central gear on said spider in mesh with the inner ones of said mating gears, and means for rotating the central gear in a direction to engage the first mentioned pairs of eccentric rollers with the flanged bottom, and then in a reverse direction to disengage the first pairs of 25 said eccentric rollers and to engage the intermediate pairs of rollers with the partially crimped bottom to complete its attachment to the container. 30

38. A device for applying a flanged bottom to a cylindrical paper container held against longitudinal movement, a shaft, a slideable sleeve on said shaft, a radial arm secured to said sleeve, a spider, a sleeve fixed in the middle portion of the 35 spider and journaled in the outer end of said arm, means for rotating the spider, two radially spaced pairs of eccentric shafts in diametrically opposite sides of said spider, flanged rollers on said eccentric shafts to partially crimp the flanged 40 bottom to said container when said eccentric shafts are rotated, two pairs of eccentric shafts diametrically journaled in said spider intermediate the first pairs of shafts, flanged rollers on the intermediate pairs of eccentric shafts to complete 45 said bottom crimping operation, mating gears on the pairs of eccentric shafts, a hollow shaft within the sleeve fixed in the spider, a gear on said hollow shaft, in mesh with the inner ones of said mating gears, a shaft within the hollow shaft and 50 formed with double spirals in its periphery, and pins projecting from the inner surface of the hollow shaft into said spirals in the inner shaft, whereby when the latter is moved axially in one direction, it will bring the first pairs of rollers 55 into engagement to partially crimp said flanged bottom to the container and maintain the intermediate pairs of flanged rollers out of engagement, and when said shaft is moved axially in a reverse direction, it will disengage the first pairs 60 of rollers and bring the intermediate pairs of rollers into engagement to complete the crimping operation.

39. In a machine for making paper containers, means for advancing and severing from a sheet 65 of paper material a unit of the desired size, a mandrel to receive and form the severed unit into a cylinder, initial and final pressure means for connecting the longitudinal ends of said cylinder into a longitudinal seam, and means for applying a bottom to said cylinder after it leaves the 70 mandrel.

40. In a machine for making paper containers, means for advancing and severing from a sheet 75 of paper material a unit of the desired size, a

mandrel to receive and form the severed unit into a cylinder, initial adhesive pressure rollers and final knurled means for connecting the longitudinal ends of said cylinder into a longitudinal seam, a bottom applying device, and means for advancing the formed cylinder along the mandrel, and from the mandrel to the bottom applying device.

41. In a machine for making paper containers, means for advancing and severing from a sheet

of paper material a unit of the desired size, a mandrel to receive and form the severed unit into a cylinder, ridged pressure means for connecting the longitudinal ends of said cylinder into a longitudinal seam, and means for applying a bottom 5 to said cylinder after it leaves the mandrel.
